Primary Examiner — Derrick Holland*Assistant Examiner* — Jennifer O King(74) *Attorney, Agent, or Firm* — Polsinelli PC**CLAIM**

The ornamental design for a storage bag, as shown and described.

DESCRIPTION

FIG. 1 is a perspective view of a storage bag;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown represent unclaimed subject matter and form no part of the claimed design.
